UNITED STATES PATENT OFFICE.

TRIMBLE DE ROODE, OF NEW YORK, N. Y.

COMBINED TYPE-WRITING AND PRINTING MACHINE.

1,292,724.

Specification of Letters Patent. Patented Jan. 28, 1919.

Application filed May 16, 1914. Serial No. 838,912.

To all whom it may concern:

Be it known that I, TRIMBLE DE ROODE, a subject of the Queen of Holland, residing in the borough of Manhattan, city, county, and State of New York, have invented certain new and useful Improvements in Combined Type-Writing and Printing Machines; and I do hereby declare the following to be a full, clear, and exact description of the invention, such as will enable others skilled in the art to which it appertains to make and use the same.

This invention relates to combined typewriting and printing machines for printing multiple copies of circular letters and inserting a salutation or other subject-matter in each letter individually. The invention is directed to the provision of an improved form of machine of this character which may be operated rapidly and conveniently, which is adapted for office use by persons of relatively little skill, with which subject-matter may be inserted with the typewriter at any point upon the sheet, and with which the printed and typewritten portions of the letters will be the same in appearance.

In accordance with the invention, a machine is provided having a movable platen adapted to support a sheet, this platen being movable to carry the sheet into coaction with the typewriting mechanism and also to carry the sheet into coaction with a type-form consisting of a multiplicity of individually assembled type. A single ink-ribbon is employed in connection with the typewriting mechanism and the type-form, this being preferably arranged to be fed intermittently in the direction of its length. By employing a single ink-ribbon for both printing operations, substantial identity in the appearance of the typewritten and printed matter is obtained. In order to permit of operating it at a substantial speed, my improved machine is provided with an automatic delivery for the printed sheets. Preferably endless carriers are employed sustaining a plurality of grippers for the sheets and these carriers are moved intermittently so as to receive a sheet from the sheet-feeding mechanism, carry that sheet to the position for writing thereon with the typewriter, then carry the sheet to the position for printing thereon with the type-form and finally deliver the sheet upon a suitable tray. The de-

livery of the sheets may be readily accomplished by causing the gripper to release the sheet when the sheet is over the delivery tray.

The invention further contemplates the provision of means for addressing envelops simultaneously with the insertion of the salutation in a letter and by the operation of typewriting the salutation. In this way, the work incident to the preparation of a number of circular letters and envelops therefor is greatly reduced and furthermore the danger of a variance between the name and address written into the circular letter and that written upon the envelop is avoided. In the preferred embodiment, an automatic feed is provided for feeding envelops successively into the position for receiving the address thereon, this address being printed through a suitable carbon strip by blows of the key-levers of the typewriting machine upon the letter-sheet which is superimposed upon the envelop.

These and other features of the invention will be better understood by reference to the following descriptions taken in connection with the accompanying drawings which show the preferred embodiment of the invention.

In these drawings, Figure 1 is a side elevation of the machine broken away in part; Fig. 2 is a longitudinal section of the machine also broken away in part; Fig. 3 is a top view of the machine also broken away in part; Fig. 4 is a perspective view of a spring hook hereinafter referred to; Fig. 5 is a perspective view of one of the grippers and the means for operating it; Fig. 6 is a front view of the machine broken away and sectioned in part; Fig. 7 is a transverse section of the machine; Fig. 8 is a top view of the envelop support; Fig. 9 is a detail view in sectional elevation showing a portion of the envelop receiver and the mechanism for feeding the envelops; Fig. 10 is a longitudinal section of the envelop support and certain of the parts adjacent thereto; Fig. 11 is an end view of the envelop support shown in Fig. 8; Fig. 12 is a transverse section of the envelop support; Fig. 13 is a view of the opposite end of the envelop support; Fig. 14 is a detail view in transverse section through the envelop container. Figs. 15 to 24 are diagrammatic views of certain of the operating parts showing successive positions

thereof; Fig. 25 is a perspective view of a removable block adapted to be fitted into an opening in the platen; Fig. 26 is an elevation of a latch hereinafter referred to.

5 In the accompanying drawings, I have shown my invention embodied in a combined typewriting and printing machine of a construction with which an Elliott Fisher typewriting machine may be readily employed and this is the type of machine which I prefer to employ, but I wish it understood that the invention is in no way limited with respect to the character of the typewriting machine employed, or the construction of 10 the apparatus adapting it for use with a typewriting machine of any particular character. The typewriting machine shown is adapted to write upon a surface underlying the machine, the whole machine being movable across the sheet step-by-step under the control of a suitable escapement mechanism. With this machine is employed a platen adapted to support the sheet in a position under the typewriting machine and this 15 platen is movable so that after the operation of the typewriting machine has been completed, the platen may be moved to carry the sheet away from the typewriting mechanism and to a position where the printing mechanism may operate thereon. Preferably the printing mechanism is arranged directly in the rear of the typewriting machine and consists of a support for a type-form and mechanism for moving the type-form to cause it to print upon the sheet. The same support for the sheet is therefore employed in connection with the type-form as that which supports the sheet in coaction with the typewriting machine, the movement 20 of this support rearwardly from the typewriting machine carrying it under the form of type.

The frame consists primarily of two side-members, 1 and 2, which are provided with 45 horizontal grooves or ways on their adjacent faces adapted to receive the lateral edges of the platen 3. This platen may slide in the grooves in the frames from the front to the rear of the machine. The frames 1 and 2 also support two transverse frames 4 (Fig. 6) upon which the typewriting machine 5 is movable from one side of the machine to the other. The movement of the typewriting machine 5 is effected by a spring 6 and 50 is under the control of an escapement mechanism. The typewriter mechanism may be of any suitable construction. In Fig. 1, I have shown keys each arranged to actuate a key-lever 7 to cause the latter to move from a vertical position about a pivot to a substantially horizontal position in which latter position the type-face thereon strikes upon the underlying ink-ribbon and sheet on the platen.

65 The form of type is supported directly in

the rear of the typewriting mechanism. It comprises a plate 8 having a plurality of parallel type-receiving channels extending across the face thereof. This plate is adapted to be detachably mounted upon the underside of a supporting plate 9. The plate 9 has bearings 10 thereon in which eccentrics 11 are received. These eccentrics are secured upon shafts 12 whose ends are journaled in bearings upon the side frames 1 and 2 of the machine. On one side of the machine the shafts 12 are extended through the bearings 10 and cranks 13 are secured thereto. The free ends of these cranks are connected by a link 14 (Fig. 2) and a coiled spring 15 is connected at one end to one of the cranks 13 and at the other end to a stud on the support for the machine. When the arms 13 are released, the spring 15 acts thereon to turn them and the shafts 12 to 70 which they are secured so that the eccentrics 11 on the shafts 12 cause the plates 9 and 8 and the type-form on plate 8 to be depressed so that the printing faces of the type engage the underlying sheet through the ink-ribbon 75 to effect printing. The arms 13 and parts connected thereto are normally held in the position corresponding to the raised or retracted position of the type-form against the tension of spring 15 by a hook on the 80 end of a lever 16 which engages a stud 17 on one of the arms 13. This hook 16 is pivotally mounted upon the rear end of one of the side-frames and has a lever 18 secured thereto whose end is adapted to be engaged 90 by an arm 103 (Fig. 3) extending rearwardly from the platen 3 so as to operate it and the hook 16 connected to it. The extent of the downward movement of the type-form is limited and is made adjustable 95 by a stop 107 (Fig. 3) adapted to be engaged by one of the arms 13 when the latter is actuated by spring 15. This stop is in the form of a screw which may be moved to any desired position and by limiting the extent of movement of the printing mechanism, it determines the character of the impression given to the sheet by the type-form. 100 A single ink-ribbon is employed both with the typewriter mechanism and the type-form. This ink-ribbon is of a width greater than the width of the type-form and its ends are wound upon rollers one of which is supported in front of the typewriter mechanism and the other of which is supported in the 105 rear of the support for the type-form. The rear roller of the ink-ribbon 19 is shown at 19 and from this roller the ribbon extends under the type-form and the typewriter and around a cross-bar 20 (Fig. 2) 110 extending between the side-frames of the machine. After passing around this cross-bar, the ribbon is carried over and around upon a roller whose shaft is journaled in 115 bearings formed upon the side-frames of 120 125 130

the machine. As seen in Fig. 2, the ribbon after passing around the cross-bar 20 is carried to the right of the roller and over and around the same. On the shaft of this 5 roller 21 is loosely mounted a pawl-carrying arm 22 and the pawl pivotally mounted on this arm is adapted to engage the teeth of a ratchet 23 which is secured to the roller 21. A spring 24 is connected to the pawl-carrying arm 22 and serves to retract it 10 after it has been actuated in a manner hereinafter described. A reverse movement of the roller 21 is prevented by a retaining pawl 25 coacting with the ratchet 23.

15 From the foregoing it will be seen that with the platen 3 in the position in which it is shown in Fig. 2, a sheet may be manually or automatically laid upon the surface of the platen and then the platen may be moved 20 to carry that sheet under the typewriting mechanism whereupon that mechanism may be operated to write any desired matter upon the sheet, locating that matter in any desired position over the entire area of the sheet.

25 This having been done, the platen may be moved to the rear so as to carry the sheet away from the typewriting mechanism and under the form of type. Just as the platen completes its movement in carrying the sheet 30 under the type-form, the arm or extension 103 projecting rearwardly from the platen engages the lever 18 so as to effect the release of the mechanism for moving the type-form. These movements of the platen may be ef- 35 fected by means of a handle projecting laterally therefrom. In the present instance such a handle is shown at 26 pivotally mounted upon the underside of the platen 3 and extending through a slot in a rack 55 (Fig. 7) hereinafter referred to secured to the under side of the platen so that the ends of the slot limit the turning movement of the handle relatively to the platen, as shown in Fig. 3. This handle consists of two parts 40 which are pivotally connected and a flat spring 27 (Fig. 7) secured to the inner part and bearing at its outer end upon the outer part holds the two parts of the handle normally in the relative positions in which they 45 are shown in Fig. 7. When in this position, a projection 28 on the handle is in position to engage one or another of a plurality of stops 29 which may be positioned in holes provided therefor along one of the walls of 50 the side frame 2. Each machine may be provided with a plurality of pins 29 varying in length as shown in Figs. 1 and 7. It will be apparent that when the handle 26 engages one of the stops 29, the rearward 55 movement of the platen is arrested and further rearward movement of the handle can be effected only by depressing the outer portion of the handle 26 against the tension of spring 27 until the handle disengages the 60 stop. In printing circulars upon the ma- 65 chine, one stop may be arranged to arrest the rearward movement of the platen when the sheet on the platen is in the position relative to the typewriting mechanism for receiving a date; another stop may be positioned to arrest the platen when the sheet is in position for receiving the salutation and one or more other stops may be arranged to arrest the movement of the platen when the sheet thereon is in position to receive other 70 matter which it is desired to insert with the typewriter mechanism.

The handle 26 is pivotally connected to the platen 3 so that its movement about its pivot may be employed for returning the 80 type-form to its raised position against the tension of spring 15. This mechanism is specially constructed so as to permit of the employment of an alining device for accurately alining the platen and the overlying 85 type-form at the time of printing from the type-form. A simple form of alining device is shown in Fig. 1 and is indicated diagrammatically in Figs. 15, 16, 23 and 24. In the construction illustrated, the alining device 90 consists of a lug 30 on the plate 9 supporting the type-form adapted to enter a notch 104 provided for its reception in the platen 3. The sides of the lug 30 and the coacting notch are inclined so that if the parts are 95 brought together with the platen out of its proper position a small amount, the platen will be caused to move relatively so as to insure its being positioned accurately with respect to the type-form. It will be seen that when such an alining device is employed, the raising movement of the type-form after the printing operation must proceed to a substantial extent before the forward movement of the platen is started. For this reason, I employ a resilient connection between the handle 26 and the restoring device for the arms 13 and spring 15 and in this connection the movement of the handle 26 about its pivot is employed. The arms 13 are 100 105 turned against the tension of spring 15 through a flexible strap 31 connected to one of the arms 13, as shown in Fig. 2. The other end of this strap is wound around a wheel 32 which is secured to a shaft 33 ex- 110 tending between the side-frames of the machine. At the opposite side of the machine, the shaft 33 has a hollow wheel 34 (Fig. 1) mounted loosely thereon and the interior wall of this wheel is connected to the shaft 33 by a flat spiral spring 35. The exterior surface of the wheel 34 is connected by means of a strap 36 with the pivoted handle 26.

The operation of these parts may be more 115 120 125 readily understood by reference to Figs. 15, 16, 23 and 24. In Fig. 23, the platen is being moved to the rear and during such movement the wheel 34 turns upon shaft 33, causing the spring 35 to be unwound with- 130

in the wheel 34. When the platen reaches the end of its rearward movement, it effects the release of the arms 13 and the type-form by rocking the lever 18 and the hook 16 and the type-form is moved downward to effect the printing by the spring 15. The arms 13 are then moved by the spring 15, and this acts through the strap 31 to rotate the shaft 33, thus causing the spring 35 to be wound as shown in Fig. 24. After the printing operation has been completed, the operator grasps the handle 26 and pulls it forwardly. The first part of this forward movement merely turns the handle 26 about its pivot, actuating strap 36 and winding up spring 35, because the platen is held against movement by having the lug 30 in the notch 104. The spring 35 thus wound up, acts through shaft 33 and wheel 32 to wind up the band or strap 31 as shown in Fig. 15 such an amount as will move the arms 13 against the tension of spring 15 a sufficient distance to cause disengagement of the lug 30 and notch 104. Such disengagement of the alining devices is shown in Fig. 16 and it will be noted that this takes place when the handle 26 reaches the end of its movement about its pivot. Thereafter further forward movement of the handle 26 causes the platen 3 to be moved forward and this is accompanied by further winding up of the band 31 and further elevation of the type-form. As shown in Fig. 3, the handle 26 has a spring 37 connected thereto so that the handle is normally held in the position in which it is shown in Fig. 3.

An automatic feed of the sheets is effected by grippers mounted on endless belts or carriers, one located at each side of the machine. These belts 40 run on rollers 39 which are carried by shafts 38 journaled in bearings in the side-frames 1 and 2. The grippers are shown at 41. Each gripper consists of two hinged jaws provided with springs 42 (Fig. 3) which act on the jaws to hold them open. One of the jaws of each gripper is of less length than the other, as indicated by the dotted lines in Fig. 5, the shorter jaw being the one which is above when the gripper is moving forward and below when it is moving rearward. The shorter jaw of each gripper is of such length that it does not contact with the rear wheels 39 and hence the gripper is open while passing around those wheels. The front wheels 39, however, are of greater width, as is shown by Fig. 3, and the short jaws of the grippers engage these front wheels 39 so that the gripper jaws are closed against the tension of their springs when they come into contact with the front wheels 39. Also, the short jaw of each gripper has extensions 69 (Fig. 5) which coact with flanges 68 at the upper edges of the side-frames 1 and 2 to hold the gripper closed as it is moving rearwardly. The belts or carriers 40 and the grippers there-

on are moved intermittently by the platen 3. For this purpose, the platen has a depression across the face thereof adjacent to the rear edge into which a gripper falls as the platen is moved forward to its forward position as shown in Fig. 2. Then when the platen is moved rearward, the gripper is carried with it, that is, it is moved from the position of the gripper shown in Fig. 2 adjacent to the ink-ribbon roller 21 to the position of the gripper shown at the rear beyond the edge of the type-form. The next step movement of the gripper last referred to would carry it around to the bottom of the machine and forward approximately half way. The next step movement of that gripper would carry it to a position almost directly under the rollers 39 at the front of the machine. In this last position, the gripper receives the edge of a sheet from the automatic sheet feeding device.

The sheets are fed to the gripper from a pile lying upon a support 42. The forward edge of this pile lies under a roller 43 which is hollow and which has a plurality of radial openings arranged in line as shown in Fig. 7. The roller 43 is supported upon a shaft 44 whose ends are carried by arms 45 and 46. One end of the shaft 44 is hollow and communicates with the space within the roller 43. This end of shaft 44 extends through the arm 45, and is connected to a pipe 47. This pipe extends to the rear of the machine, and is connected to the rear end of a cylinder 48 whose front end is open. This cylinder is mounted upon the inner side of the side-frame 2. A piston 49 is mounted upon the under side of the platen 3 in position to coact with the cylinder 48; when the platen has reached the end of its rearward movement, the piston 49 will be in the rear closed end of the cylinder 48. When the forward movement of the platen starts, the piston 49 will tend to draw air into the cylinder 48 through the tube 47 and the small, radial openings 50 (Fig. 7) in the roller 43, so that the top sheet of the pile will be held tight against the surface of the roller 43.

The arms 45 and 46 carrying the roller 43 are loose upon a shaft 51 (Fig. 2) extending between two links 52, which are loose upon a shaft 53 one end of which is journaled in the side-frame 1 and the other in a standard 105 (Fig. 7) mounted on the base. The shaft 53 has gears 54 thereon, one of which is adapted to be engaged and operated by a rack 55 mounted upon the under side of the platen 3. The gears 54 mesh with similar gears 56 which are secured to the shaft 51. This shaft is extended through the link 52 on one side of the machine and carries a bevel gear 57 (Fig. 7) on its extreme end. This gear meshes with a similar gear upon a shaft 58 which is connected by bevel gears 130

59 with the shaft 44 of the roller 43, the shaft 58 being mounted in bearings secured to the arm 46 which carries the roller 43.

The rack 55 is of such length that the 5 rearward movement of the platen carries the rack beyond the gear 54. On the forward movement of the platen, the piston 49 creates a suction upon the top sheet of the pile, and immediately thereafter, the rack 55 engages 10 one of the gears 54. The first effect of the turning movement thus imparted to the gears 54 is to swing the arms 52 rearward against the pin or stop 106 (Fig. 2) so that the gears 56 pass bodily from the position 15 shown in Fig. 16 relative to the gears 54 to the position shown in Fig. 17. This movement of the arms 52 accompanied by shifting of the gear 56 takes place because the parts driven from the gear 56, including the 20 roller 43, impose a load upon the gear 56 which holds that gear against rotation until the shifting movement of the gear and the arms 52 is arrested by the stop 106. This bodily movement of gears 56 and the shaft 25 51 on which they are mounted, causes rearward, lengthwise movement of the arms 45 and 46 and the roller 43 which at this time is gripping the top sheet of the pile. During this bodily movement of the roller 43, 30 the roller is rotated by the rack 55 through the gears 54, 56, 57 and 59 and as the roller carries the top sheet with it, the end of that sheet is rolled up to a position approximating a right angle to the underlying sheets of 35 the pile. This movement of the roller 43 and the front edge of the top sheet is shown in Figs. 16 and 17. The continuation of this rotational movement of roller 43 effected by rack 55 causes the top sheet of the pile whose 40 end has been separated from the underlying sheets to be fed forward from the pile. This feeding movement of the sheet is effected by providing a stop to limit the movement of the underlying sheets, and by having 45 the surface of the roller 43 covered with rubber or other suitable material which will grip the top sheet.

The stop for the sheet pile consists of a bar 61 extending across the machine and 50 provided with downward projections as shown in Fig. 7. This bar is carried by arms 62 which are secured to a rod 63 extending between and journaled in suitable bearings formed on the support 42 for the 55 sheet-pile. A spring 64 (Fig. 7) is coiled about this rod 63 and connected thereto so that the spring acts upon the arms 62 in a direction to raise the bar 61. On one of the arms 62, is an upwardly extending spring 60 65, Figs. 1 and 7, adapted to coact with a cam 66 secured to the under side of the platen 3. This cam engages the spring arm 65 immediately after the roller 43 has raised the front edge of the topmost sheet as above 65 described and the cam acts upon the spring

65 to depress the bar 61 against the tension of its spring 64, so that the bar is carried down upon the forward edge of the pile of sheets underlying the top sheet. This movement of bar 61 is shown in Figs. 17 and 70 18. Shortly after the bar is moved down upon the top of the sheet pile, the piston 49 is drawn completely out of the cylinder 48 thus relieving the suction upon the sheet and the end of the sheet falls upon the bar 75 61. As the platen continues to move forward, the rotation of roller 43 continues, the axis of the roller remaining fixed, and the sheet is fed over the surface of the pile and well into the space between the jaws of the 80 gripper 41 adjacent to the forward edge of the sheet pile. To insure proper entrance of the edge of the sheet into the gripper, guides are provided as shown at 67 in Fig. 2.

The grippers 41 are of such length that 85 their ends engage the rollers 39. When the feeding movement of the grippers starts, the gripper which has just received a sheet from the sheet pile is immediately closed by its contact with the front rollers 39 so that it 90 grips the sheet. The sheet is, therefore, carried around by this gripper to the upper edges of the side-frames and rearward until the gripper assumes the position underlying the forward ink-ribbon roller. When the 95 gripper moves away from the rollers 39, it is maintained in the closed position by the flanges 68 projecting inwardly from the upper edges of the side-frames 1 and 2, and engaging the extensions 69 of the lower jaw 100 of the gripper which extensions bear against the under sides of the flanges 68 so as to maintain the gripper in the closed condition throughout its rearward movement from the forward rollers 39 to the rear rollers 39. 105

Just as the first movement of the gripper and the sheet carried thereby is completed, the gripper passes under the teeth of hooks 70' (Figs. 4 and 7) one located at each side of the machine. Each of these hooks is 110 made of spring metal and the forward edge of the tooth thereof is inclined so that the teeth will be raised by the gripper as the latter passes rearward under the teeth. Immediately after the gripper passes the teeth 115 120 the latter drop down in front of them so as to prevent forward movement of the gripper and the sheet. Thereafter, the platen may be moved forward, and as it is moved, its forward inclined edge engages 125 the gripper and raises it slightly a distance sufficient to permit the platen to pass under it. When the platen has been moved all the way forward, it lies under the sheet held by the gripper and thereafter forms a support for the sheet during the operations of printing and of writing upon the sheet with the typewriter.

As the platen is moved forward, the sheet 130 which has just been printed upon from the

type-form is held in the rearward position to which it was previously moved, as shown in Fig. 18; and when the forward movement of the platen is completed, the forward edge of this sheet is unsupported and drops down upon a suitable receiving tray in the manner indicated in Fig. 19.

When the next movement of the grippers commences, the gripper holding this sheet 10 will be carried down away from the flanges 68 in the manner indicated in Fig. 5 so that the spring of that gripper will be allowed to open the jaws of the gripper. This effects the complete release of the sheet and 15 the latter is deposited upon the receiving tray in the manner shown in Figs. 20 and 21.

After typewriting more or less of the matter which it is desired to write with the typewriter, it may be desired to inspect what 20 has been written. When the gripper drops into the groove in the platen, the latter is in the position shown in Fig. 2. To type-write on the sheet, the platen is moved rearwardly a short distance to carry the sheet 25 under the typewriter. To inspect what has been written, the platen is moved forward again, two latches being provided one at each side of the platen, for insuring that the gripper will then move with the platen. 30 One of the latches is shown in Fig. 26. These two latches 101 are pivotally mounted upon the rear edge of the platen and their ends enter the grooves in the side-frames in which the edges of the platen move. These 35 latches have projections 102 on their upper edges which lie behind the gripper when the latches are in the full line position shown in Fig. 26. The rear ends of the ways in which the ends of the latches move are depressed as shown at 107 in Fig. 2 so that 40 when the latches reach these depressed ends they are lowered to depress the projections 102 below the gripper and allow the platen to be moved forward independently of the 45 gripper.

As indicated in Figs. 3 and 7, the rack 55 and cam 66 have their upper edges cut away for a short distance to provide a slot through which the handle 26 extends.

50 The machine constructed in the manner above described may be employed for printing circular letters and inserting in each of the copies an individual salutation or any other matter which it is desired to insert 55 specially so as to permit of making changes in the inserted matter on different copies of the circular letter.

In order to further facilitate the work of sending out circular letters, I have provided 60 means whereby an envelop may be addressed while writing the salutation upon a letter sheet. This envelop directing mechanism involves the provision of a receptacle for a stack of envelops, a feeding means for feeding envelops successively from the receptacle 65

to a position underlying the sheet on the platen and a transfer sheet, such as a strip of carbon paper, whereby the characters printed upon the letter-sheet by the key-levers of the typewriter will be printed upon the face of the envelop through the carbon sheet. 70

Referring to Fig. 6, it will be seen that at one side of the machine is a laterally extending frame 69 which supports a receptacle 70, in which a stack of envelops may be placed. The receptacle 70 is supported upon a pair of parallel bars 71 which are pivotally connected at their outer ends at 72 to a block 73 which is pivotally mounted upon the frame 69 so as to turn about a vertical axis. The bars 71 have grooves upon their adjacent faces as shown in Fig. 14, and in these grooves a forwarding device 74 is adapted to reciprocate. This forwarding device is connected to and actuated by a belt 75 which runs on pulleys mounted upon the frame 69. The shaft of the inner one of these pulleys is extended rearwardly and has a bevel gear 76 (Fig. 3) thereon 90 which meshes with a similar gear on the end of the shaft 53, which shaft is extended through the side-frame 1 of the machine. The shaft 53 is rotated first in one direction and then in the other as heretofore explained and therefore, operates through the gears 76 and the belt 75 to reciprocate the forwarding device 74. 95

On the forwarding device 74 is a tongue 77 consisting of a piece of thin sheet-metal. 100 At its free end this piece 77 is extended laterally so as to provide side portions 78 which guide the tongue 77 as it is moved with the forwarding device 74. The receptacle 70 for the envelops has the outer wall 105 thereof cut away as is shown in Fig. 9 and at the sides of this slot in the wall of the box 70 are guides 79. As the forwarding device 74 and tongue 77 are moved to the right from the position in which they are 110 shown in Fig. 9, the lateral extensions 78 of the tongue 77 engage the guides 79 and ride up upon those guides. This causes the edge of the tongue 77 to be raised so that it will pass over the edge of the lowermost envelop in the box 70. Then when the wings 78 pass over the guides 79, the tongue 77 will grip the envelop between it and the surface of the forwarding device 74. Then as the forwarding device moves to the right, 115 the envelop will be carried with it.

As the envelop moves thus, its forward edge passes under a plate 80 and over the surface of a support 81. This support 81 is made from a block and its cross sectional 125 shape is that indicated in Fig. 12 from which it will be seen that the upper lengthwise edges of the block are inclined at an angle of approximately 45 degrees. The support 81 has a lengthwise opening 82 cut 130

therein, adapted to receive a strip of carbon paper 83, one end of which is wound upon a reel 84 secured to the under side of the support 81. At the inner end of the support 81, 5 the strip of carbon paper 83 passes up to the upper face of the support and over that face to another reel 85 upon which it is wound. This reel is mounted in standards rising from the plate 80. This plate 80 is secured 10 to the block 81 and also it is pivotally connected to the bars 71 forming the support for the box 70 and the guide for the reciprocating forwarding device 74. This pivotal connection is effected by a pivot pin 15 86 passing through the plate 80 and also through a cross-bar 87 extending between the bars 71. The plate 80 has ears formed thereon which support a rod 88 constituting a guide for the carbon strip 83.

20 It will be seen that when the forwarding device moves to the right, the envelop gripped thereby is fed under the plate 80 and over the surface of the support 81. As it moves over the surface of the support, the 25 portions along its lower edges are bent downwardly by suitable guiding surfaces 89 on the support 81, which are shaped to form a slot 90, the central portion of which is horizontal and the side portions of which are inclined 30 downwardly. When the envelop is in this position, it underlies the sheet upon the platen, the carbon strip 83 lying between the two; therefore, the operator may operate the typewriter to write on the sheet and the 35 characters will be printed, not only upon the sheet, but also upon the envelop through the carbon strip. After this has been done, the movement of the sheet to the position for printing thereon from the type-form, 40 causes the forwarding device 74 to be moved to the left. When it does so move, it carries the envelop with it. The envelop is shown at 91 in Fig. 10 gripped by the tongue and the forwarding device 74.

45 When the forward device moves to the left, the extensions 78 of the tongue 77 pass under resilient projections 92 upon the bottom of the receptacle 70. The extensions 78 pass readily over these projections 92 when 50 the envelop is being moved to the right; but when the envelop is being retracted, they pass under the projections 92 so that the envelop is carried to the left under the bottom of the box 70. When the forwarding 55 device 74 nears the end of its movement to the left, the edges of the envelop engage stops 93 (Fig. 9) and the envelop is thus held against movement with the forwarding device until it is released by the tongue 77, 60 whereupon it drops by gravity into a suitable receptacle.

By reference to Figs. 2 and 3, it will be seen that the platen 3 has a slot cut therein extending a portion of the way across the 65 platen and that the side-walls of this slot are inclined. The cross sectional shape of this slot in the platen is substantially the same as that of the block 81 of the envelop feeding and supporting mechanism. This block 81 extends through an opening 94 70 in the side-frame 1 of the machine. This opening 94 is of substantially greater size than the block 81, but its sides are inclined, giving it a shape similar to that of the support 81. The support 81 is capable of movement both vertically and horizontally within this opening 94. Its upward movement carries it up into the slot in the platen and while in that slot it may be moved horizontally with the platen. When the slot in the 80 platen comes over the support 81 the latter is moved upwardly into the slot by a plunger 95 (Fig. 6), located in a suitable guide-way in the side-frame 1, and acted upon by a spring 96. The upper end of the plunger 85 95 bears against the under side of the support 81. This upward movement of the support 81 effected by the spring 96 and plunger 95 is permitted by the pivotal mounting of the support 81 and bars 71 to which the 90 support is secured so that they may turn about a horizontal axis 72. When the support 81 has been raised vertically by spring 96, it may move horizontally with the platen by reason of the pivotal connection 95 of the support 81 with the bars 71 at 86 and the pivotal connection of the bars 71 to the frame 69 at 73. When the writing of the salutation has been completed and with it the addressing of the envelop, the platen 3 100 is moved rearwardly and the support 81 which is then located in the slot in the platen engages the inclined wall at the rear end of the opening 94, and is caused to move downwardly by that inclined wall to a position 105 in which it lies below the under side of the platen and permits the latter to move over it.

The vertical movement of the support 81 is utilized to cause feeding of the carbon strip 82. For this purpose, the shaft of the reel 84 is provided with a ratchet 97 (Fig. 6) and loose on the shaft of this reel is a pawl-carrying arm 98, on which is pivoted a pawl adapted to engage the teeth of the ratchet 97. The end of the arm 98 is adapted to 110 engage a bracket 99 secured to a side-frame of the machine. When the support 81 moves downwardly, the arm 98 engages bracket 99 and is turned thereby a distance sufficient 115 to cause the pawl to turn the ratchet a distance corresponding to one tooth of the ratchet.

The slot in the platen for the reception of the envelop support is preferably provided in a removable block 108 (Figs. 2 and 3) 120 125 which is adapted to be removably mounted in a rectangular opening in the platen by means of tongues and grooves. When the machine is not to be used for addressing envelopes, the block 108 is removed and a solid 130

block 109 (Fig. 25) is inserted in the opening in the platen in its place.

The operation of the machine will be best understood by reference to the diagrammatic views, Figs. 15 to 20. In Fig. 15, the parts are shown in the positions they assume immediately after the sheet has been printed upon with the type-form and the handle 26 has been drawn forward far enough to raise 10 the type-form just enough to effect disengagement of the alining devices. The piston 49 is still at the rear end of the cylinder for the platen has not been moved forward at all, and the rack 55 is displaced rearwardly 15 from the gear 54. One gripper holds the sheet which has been printed upon, another gripper holds a sheet in position for coaction with the platen when the latter is moved forward, another gripper is open ready to 20 receive a sheet from the sheet feeding apparatus, and the fourth gripper is in the course of its movement forward to receive a sheet.

In Fig. 16, the platen has been moved forward just far enough to carry the rack 55 25 into engagement with the gear 54, and during this movement the piston 49 has moved within the cylinder 48 so as to create a suction upon the top sheet of the sheet pile.

Fig. 17 shows the parts after the platen has moved a little farther forward. During this movement the rack 55 acts upon the gear 54 to cause the gear 56 and the parts connected thereto to be swung rearwardly. 30 This causes the roller 43 to be swung rearwardly, but as the latter has gripped the top sheet of the pile, it is turned on its axis so as to raise the end of the sheet to a vertical position. This Fig. 17 also shows the outline 40 of the opening 94 in the side-frame 1, and the support 81 projecting through that opening. Also, in this view and the succeeding views, the heavy black line 100 indicates the end of the envelop.

In Fig. 18, the platen has moved forward 45 and the cam 66 has engaged the spring-arm 65 so as to depress the bar 61 into engagement with the sheet pile. Also the plunger 49 has moved out of the cylinder so that 50 the suction of the top sheet against the surface of the roller 43 has been relieved. The continued movement of the rack 55 in mesh with the gear 54 causes the roller 43 to be rotated and this roller feeds the top sheet 55 over the stop 61 and down into the open gripper.

In Fig. 19, the feeding movement of the sheet by the roller 43 has been completed, and the platen has reached the forward end 60 of its movement. While the platen is being moved forward, the support 81 is moved upwardly into the slot by its spring-actuated plunger 95, and is carried with the platen until it engages the forward inclined wall 65 of the opening 94. When the support 81

engages this inclined wall, the latter acts as a cam to depress the support 81 in the end of the opening 94 opposite to that in which it is shown in Fig. 17. Also, during this forward movement of the platen, the envelop forwarding device has been actuated in the manner above-described so as to feed an envelop down into the support 81. The envelop is so indicated by the heavy line in Figs. 18 and 19. Also, the withdrawal of 70 the platen from under the sheet printed upon by the type-form allows that sheet to drop as shown in Fig. 19 except at its rear edge which is held by the gripper.

When the platen reaches the limit of its 80 forward movement, the gripper which is holding the sheet which overlies the platen, drops into the groove at the rearward edge of the platen so that when the platen is moved rearward, this gripper and the sheet 85 carried thereby and the endless carriers affixed to the grippers are moved with the platen. Fig. 20 shows the parts after the platen has been moved rearward a distance sufficient to carry the sheet on the platen 90 into coaction with the typewriting machine, that portion of the sheet on which the salutation is to be written being at the printing point of the typewriter. As the platen reaches this position, the envelop support 95 95 100 105 110 115 120 125 130 81 is moved up into the slot in the platen. The operator may then write the salutation upon the sheet and this will be written upon the envelop by means of the carbon strip at the same time. It will be noted also in Fig. 20 that the sheet last printed upon has been released by the gripper and is dropped upon a suitable support. In Fig. 20, a key-lever of the typewriting machine is shown in position for writing a letter of the first line of the salutation. In Fig. 21, the platen has been moved rearward a small amount and the key-lever is in position for writing a letter of the last line of the salutation.

When the platen is moved beyond the 110 Fig. 21 position, the rack 55 engages the gear 54, and thereafter shifts the position of the gear 56 and the roller 43 connected thereto so that those parts will be in the position shown in Fig. 15 in readiness for 115 another sheet-separating operation. This change in the position of gear 56 is shown in Figs. 21 and 22. As the platen moves from the Fig. 20 to the Fig. 21 position, the support 81 moves horizontally with it, but 120 as the platen moves from the Fig. 21 to the Fig. 22 position, the support 81 is moved downward so that it lies below the level of the platen and the latter is moved along to the position for printing on the sheet carried thereby with the type-form.

In Fig. 23, the platen is nearing the end of its rearward movement carrying the sheet under the type-form. In Fig. 24, the platen has reached the end of its rearward move- 125 130

ment and has engaged the lever 18 so as to release the detent 16. On such release of the detent 16, the arms 13 are actuated as heretofore described so as to cause the type-form 5 to be moved down upon the sheet and to print upon the sheet through the ink-ribbon. Also this last movement of the platen carries the cam 66 beyond the spring-arm 65, so that the stop 61 is raised by its 10 spring 64.

It will thus be seen that the machine consists of a movable platen for supporting a sheet of paper, a typewriting machine for writing upon the paper so supported, and 15 means for supporting and moving a type-form located in such a position that the platen may be moved to carry the sheet so written upon with the typewriter into coaction with the type-form, so that the sheet 20 may be printed upon with the type-form. The mechanism is such that one or any number of different parts of the letter differently located with respect to the edges of the sheet may be written with the typewriting 25 mechanism. Also, both the printing from the type-form and the printing with the typewriter are effected through the same ink-ribbon so that the color of the printed matter is the same over the entire surface 30 of the sheet. The work of preparing circular letters partly typewritten and partly printed is greatly facilitated by the provision of the automatic feed of the sheets into the printing position and the automatic 35 delivery of the printed sheets.

If desired, the mechanism may be constructed in the manner herein shown so as to combine with the mechanism for printing the letter sheets an automatic feed for 40 envelopes whereby the envelopes may be positioned so as to print addresses thereon simultaneously with the printing of the salutation upon the letters.

I claim:

45 1. In a typewriting and printing machine, the combination of a typewriting mechanism, a printing mechanism including means for supporting a form of type with the several type thereof in a plane, a flat platen for supporting a sheet of paper movable to carry the sheet into coaction with the typewriting mechanism and into coaction with the printing mechanism, a single ink ribbon of substantial width and means for supporting the 50 ink-ribbon in position for printing therefrom upon the sheet carried by the platen both with the typewriting mechanism and with the printing mechanism.

60 2. In a typewriting and printing machine, the combination of a platen for supporting a sheet of paper, a typewriting mechanism movable as a whole step by step in one direction, a printing mechanism and means for supporting the platen permitting movement 65 thereof in a direction transverse to the direc-

tion of movement of the typewriting mechanism to carry the platen into position for coaction with the typewriting mechanism and into position for coaction with the printing mechanism. 70

3. In a typewriting and printing machine, the combination of a support, a flat platen for supporting a sheet of paper mounted upon the support and adapted to be moved thereon in a straight line in one direction, 75 a typewriting machine mounted upon the support in position to write upon a sheet on the platen and movable on the support in a different direction and a printing mechanism mounted upon the support in 80 position to coact with the platen when the latter has been moved away from the typewriting mechanism.

4. In a typewriting and printing machine, 85 a support, a flat platen mounted upon the support and movable thereon in one direction, a typewriting mechanism mounted upon the support and movable in another direction above the platen, means for supporting a flat type-form with the printing faces of 90 the type lowermost in position to coact with the platen when the latter has been moved out of coaction with the typewriting mechanism and means for moving the type-form and platen relatively to effect the printing. 95

5. In a typewriting and printing machine, the combination of a typewriting mechanism, a printing mechanism, a platen for supporting a sheet of paper movable to carry the sheet into coaction with the typewriting mechanism and into coaction with the printing mechanism and means operated automatically by movement of the platen into coaction with the printing mechanism for causing operation of the printing mechanism to print 100 upon a sheet carried by the platen. 105

6. In a typewriting and printing machine, 110 a support, a platen mounted on the support and movable in one direction thereon, a typewriting mechanism movable as a whole in another direction for writing upon a sheet supported by the platen, a printing mechanism in position to coact with the platen when the latter has been moved away from the typewriting mechanism, a single ink-ribbon of substantial width supported in position to coact with the typewriting mechanism and the printing mechanism and means actuated by the movement of the platen into coaction with the printing mechanism for causing actuation of the printing mechanism to print upon a sheet carried by the platen. 115

7. In a typewriting and printing machine, 125 the combination of a pair of supports, a platen movable lengthwise thereon, a typewriting mechanism carried by the supports in position to write upon a sheet supported by the platen and movable transversely of said supports, a support for a type-form 130

mounted on said supports in the rear of the typewriting mechanism, an ink-ribbon of substantial width supported at one end in front of the typewriting mechanism and at 5 the other end in rear of the support for the type-form and means for causing relative movement of the support for the type-form and the platen.

8. In a typewriting and printing machine, 10 the combination of a typewriting mechanism, a support for a type-form, a platen for supporting a sheet of paper movable to carry the sheet into coaction with the typewriting mechanism and into coaction with the type- 15 form, a spring for causing relative movement of the support for the type-form and the platen and means actuated by movement of the platen into position for coaction with the type-form for permitting operation of 20 said spring.

9. In a typewriting and printing machine, the combination of a pair of supports, a platen movable lengthwise thereon, a typewriting mechanism movable crosswise of the 25 supports above the surface of the platen, a support for a type-form mounted in rear of the typewriting mechanism, an ink-ribbon supported at one end in front of the typewriting mechanism and at the other end in 30 rear of the support for the type-form, a spring for effecting relative movement of the platen and the support for the type-form and means actuated by the movement of the platen for permitting operation of said 35 spring.

10. In a typewriting and printing machine, a platen for supporting a sheet movable bodily over a prescribed path, a typewriting mechanism and a printing mechanism located on the same side of the path 40 of movement of the platen and displaced one from the other in the direction of the path of movement of the platen, the platen being movable to carry the sheet bodily from 45 one mechanism to the other so that the two mechanisms may print successively upon the same portion of the sheet, means for positioning the platen with respect to the typewriting mechanism and means for operating 50 the printing mechanism to print with the type thereof upon the sheet.

11. In a typewriting and printing machine, the combination of a typewriting mechanism, a printing mechanism mounted 55 adjacent thereto, a platen for supporting a sheet movable to carry the sheet into coaction with the typewriting mechanism and into coaction with the printing mechanism, an ink-ribbon of substantial width supported at its ends on the non-adjacent sides of 60 the type-writing mechanism and the printing mechanism so that the intermediate portion of the ribbon is in coaction with said mechanisms, and automatic sheet-feeding

devices for feeding sheets upon the surface 65 of said platen.

12. In a typewriting and printing machine, the combination of a support, a platen movable lengthwise upon the support, a typewriting mechanism movable 70 crosswise of the support over the surface of the platen, a support for a type-form mounted on the support in rear of the typewriting mechanism, an ink-ribbon supported at one end in front of the typewriting mechanism and at the other end in rear of the support for the type-form, means for feeding sheets automatically upon the surface 75 of the platen and means for effecting relative movement of the platen and the support for the type-form.

13. In a typewriting and printing machine, the combination of a typewriting mechanism, a printing mechanism, a platen for supporting a sheet of paper movable to 85 carry the sheet into coaction with the typewriting mechanism and into coaction with the printing mechanism, means for supporting an ink-ribbon in position to coact with both the typewriting mechanism and the 90 printing mechanism, an automatic sheet-feeding mechanism for feeding sheets upon the surface of the platen and means for effecting the delivery of the sheets after they have been printed upon by the printing 95 mechanism.

14. In a typewriting and printing machine, the combination of a typewriting mechanism, a support for a type-form, a platen movable to a position in front of the 100 typewriting mechanism, to a position under the typewriting mechanism and to a position under the support for the type-form, means for feeding sheets upon the surface of the platen and for causing such sheets to 105 be carried with the platen into coaction with the typewriting mechanism and the support for the type-form and means for precluding return movement of a sheet with the platen.

15. In a typewriting and printing machine, the combination of a typewriting mechanism, a printing mechanism, a platen adapted to hold a sheet in coaction with the typewriting mechanism and movable to carry the sheet into coaction with the printing mechanism, means for insuring movement of the sheet with the platen from the typewriting mechanism to the printing mechanism and means for precluding return movement of the sheet with the platen. 110 115

16. In a typewriting and printing machine, a platen for supporting a sheet movable bodily over a prescribed path, a typewriting mechanism and a printing mechanism located on the same side of the path of 120 movement of the platen and displaced one from the other in the direction of the path of movement of the platen, the platen being 125

- movable to carry the sheet bodily from one mechanism to the other so that the two mechanisms may print successively upon the same portion of the sheet, means for positioning the platen with respect to the typewriting mechanism, means for moving the platen step by step while in coaction with the typewriting mechanism to affect line spacing, and means for operating the printing mechanism to print with the type there-of upon the sheet. 65
- 5 17. In a typewriting and printing machine, the combination of a typewriting mechanism, a printing mechanism, a platen for supporting sheets in coaction with both the typewriting mechanism and the printing mechanism said platen being movable relatively to the typewriting mechanism to effect line spacing and to carry a sheet from 70 one of said mechanisms to the other, so that both mechanisms may print upon the same portion of the sheet, and a plurality of adjustable stops for arresting movement of the platen in selected positions of line spacing 75
- 10 20 25 18. In a typewriting and printing machine, the combination of a typewriting mechanism, a printing mechanism, a single platen for supporting a sheet movable to one position for supporting a sheet in coaction with the typewriting mechanism and to a second position for supporting the sheet in coaction with the printing mechanism, and an alining device for insuring proper alinement of the printing mechanism and the platen. 80
- 30 35 19. In a combined typewriting and printing machine, the combination of a typewriting mechanism, a support for a type-form, a platen for supporting a sheet movable to one position to carry the sheet into coaction with the typewriting mechanism and to a second position to carry the sheet into coaction with the printing mechanism, a single ink-ribbon coating with both the typewriting mechanism and the type-form on said support and an alining device for alining the type-form on said support and the platen. 85
- 40 45 50 20. In a typewriting and printing machine, the combination of a typewriting mechanism, a printing mechanism, a platen for supporting a sheet movable from a position in coaction with the typewriting mechanism to a position in coaction with the printing mechanism, a sheet-feeding mechanism and means operated by the return movement of the platen for actuating the sheet-feeding mechanism. 90
- 55 60 21. In a typewriting and printing machine, the combination of a typewriting mechanism, a printing mechanism, a pair of endless carriers, grippers on the carriers and means for actuating the carriers to carry sheets into coaction with the typewriting and printing mechanisms successively. 95
22. In a typewriting and printing machine, the combination of a typewriting mechanism, a printing mechanism, a platen movable into positions for coaction with the typewriting and the printing mechanisms, a carrier for sheets, and means actuated by the movement of the platen for operating the carrier. 100
23. In a typewriting and printing machine, the combination of typewriting and printing mechanisms, a movable platen adapted to coact with both the typewriting and the printing mechanisms, a gripper for holding a sheet, a sheet-feeding mechanism, means operated in correspondence with the movement of said platen for actuating the sheet-feeding mechanism to feed sheets automatically to said gripper and means co-operating with said platen for moving the gripper to carry a sheet held thereby into position to be supported by the platen. 105
24. In a typewriting and printing machine, the combination of typewriting and printing mechanisms, a platen movable into coaction with the typewriting and with the printing mechanisms, a pair of endless carriers movable in correspondence with the movement of the platen, grippers on the carriers, a sheet-feeding mechanism for feeding sheets to the grippers and means operated by movement of the platen for actuating the sheet-feeding mechanism. 110
25. In a typewriting and printing machine, the combination of typewriting and printing mechanisms, a platen movable into coaction with the typewriting mechanism and into coaction with the printing mechanism, a gripper for a sheet and means supporting said gripper actuated by movement of the platen for moving the gripper in one direction, the movement of the gripper in the opposite direction being precluded. 115
26. In a typewriting and printing machine, the combination of typewriting and printing mechanisms, a pair of endless carriers, grippers on the carriers for carrying sheets to the typewriting and printing mechanisms successively, means for automatically opening and closing the jaws of the grippers and means for actuating the carriers. 120
27. The combination of a typewriting mechanism, a printing mechanism, means for supporting a sheet, said means and said mechanisms being movable relatively so that a sheet on said means may be positioned for coaction with either of said mechanisms, a piece of transfer material supported in position for coaction with the typewriting and printing mechanisms and with a sheet on said supporting means, a second piece of transfer material at the striking point of the 125

key levers of the typewriting mechanism, means for positioning envelops for coaction with the second piece of transfer material and with the typewriting mechanism, and 5 means for operating the printing mechanism to print on a sheet on said supporting means.

28. The combination of a typewriting mechanism, means for supporting a sheet in position to coact with the type thereof, a 10 piece of transfer material supported in position for coaction with said mechanism and sheet, means for feeding envelops successively to a position under the sheet coacting with the type, means for supporting a second 15 piece of transfer material between an envelop so fed and the sheet of paper, and means for printing upon the sheets from a type-form.

29. The combination of a typewriting mechanism, means for supporting a sheet in 20 position to coact with the type thereof, a piece of transfer material supported in position for coaction with said mechanism and sheet, a support for holding an envelop under the sheet, means for feeding envelops into the support and withdrawing them from the same, means for supporting a second piece of transfer material between the sheet and an envelop in the envelop-support, 25 and means for printing upon the sheets from a type-form.

30. In a typewriting and printing machine, the combination of typewriting and printing mechanisms, a plate for supporting 35 a sheet movable into coaction with the typewriting and printing mechanisms, envelop-feeding mechanism for feeding envelops successively to a position underlying a sheet on the platen, means for supporting a piece of 40 transfer material between the sheet and envelop and means actuated by movement of the platen for operating the envelop-feeding mechanism.

31. In a typewriting and printing machine, the combination of typewriting and printing mechanisms, a platen movable into 45 positions for coaction with the typewriting and printing mechanisms and having a slot therein, an envelop-support movable into 50 and out of said slot and movable with the platen while in the slot and means for feeding envelops into the envelop-support, said envelop-support being adapted to lie within the slot when the platen is in position for 55 coaction with the typewriting mechanism.

32. A typewriting and printing machine comprising the combination of typewriting and printing mechanisms, a platen for supporting a sheet in coaction with the type- 60 writing and printing mechanisms, automatic sheet-feeding mechanism for feeding sheets successively into coaction with one of said mechanisms, envelop-feeding mechanism for feeding envelops successively to a position

underlying a sheet fed by the sheet-feeding mechanism and means for supporting a piece of transfer material between the sheet and envelop. 65

33. A typewriting and printing machine comprising the combination of typewriting and printing mechanisms, a platen movable to positions for supporting a sheet in coaction with the typewriting mechanism and the printing mechanism, envelop-feeding mechanism for feeding envelops successively to a position underlying a sheet on the platen and means for delivering the sheets and envelops. 70

34. A typewriting and printing machine comprising the combination of typewriting and printing mechanisms, a platen movable to positions for supporting a sheet in coaction with the typewriting mechanism and the printing mechanism, sheet-feeding mechanism for feeding sheets successively upon 80 said platen, envelop-feeding mechanism for feeding envelops successively to a position underlying a sheet fed by the sheet-feeding mechanism and means for delivering the sheets and envelops after they have been 85 printed upon. 90

35. A typewriting and printing machine comprising the combination of typewriting and printing mechanisms, a platen for supporting a sheet movable into coaction with the typewriting and printing mechanisms, means for feeding sheets upon the surface of the platen, envelop-feeding mechanism for feeding envelops successively to a position underlying a sheet on the platen, and means 95 for supporting a piece of transfer material between the sheet and envelop. 100

36. A typewriting and printing machine, comprising the combination of typewriting and printing mechanisms, a platen for supporting a sheet movable to carry the sheet into coaction with the typewriting mechanism and into coaction with the printing mechanism and means for holding a sheet immovable upon the platen throughout the 105 operation of printing a plurality of lines upon the sheet with the typewriting mechanism and the operation of printing upon the sheet with the entire type-form of the printing mechanism. 110

37. A typewriting and printing machine comprising the combination of typewriting and printing mechanisms, a platen for supporting a sheet while printing thereon with both the typewriting and the printing mechanisms and means for holding a sheet immovable upon the platen throughout the operation of printing a plurality of lines upon that sheet with the typewriting mechanism and the operation of printing upon the 120 sheet with the entire type-form of the printing mechanism. 125

38. In a typewriting and printing ma-

chine, the combination of a typewriting mechanism, a printing mechanism including means for supporting a form of type with the several type thereof in a plane, a single piece of transfer material supported in position for coaction with both the typewriting mechanism and the printing mechanism, a flat platen for supporting a sheet in coaction with both the typewriting mechanism and the printing mechanism, said platen being movable to carry a sheet bodily from one mechanism to the other so that both mechanisms may print upon the same portion of the sheet, means for operating the printing mechanism to print from said piece of transfer material upon the sheet, and means for feeding sheets upon the surface of the platen; substantially as described. 15

In testimony whereof I affix my signature, in presence of two witnesses.

TRIMBLE DE ROODE.
